UNITED STATES PATENT OFFICE.

FRANK A. LUNDQUIST, OF CHICAGO, ILLINOIS, ASSIGNOR, BY MESNE ASSIGNMENTS,
TO HENRY S. CONRAD, TRUSTEE.

AUTOMATIC TELEPHONE EXCHANGE.

Application filed October 27, 1919. Serial No. 333,514.

To all whom it may concern:

Be it known that I, FRANK A. LUNDQUIST, a citizen of the United States of America, and a resident of Chicago, county of Cook, and State of Illinois, have invented certain new and useful Improvements in Automatic Telephone Exchanges, of which the following is a specification.

My invention relates to automatic telephone exchanges, and has for its object improvements in such organizations. The present invention is confined to the parts of the exchange which are employed in the preliminary stages of making a call.

15 In the accompanying drawings—

Fig. 1 is a side elevation of one of the line switches and associated parts in making a trunk selection;

Fig. 2 is an enlarged section on line 2—2 of Fig. 1, together with some additional parts;

Fig. 3 is a side elevation of a fragment of the apparatus on a selector;

Fig. 4 is an end elevation of a part of Fig. 3;

Fig. 5 is an elevation in the direction 5 of Fig. 1, showing one line switch and a part of a second one together with additional apparatus in diagram for a group of one hundred line switches; and

Figs. 6, 7, 8, 9 and 10, taken together, with Fig. 6 at the bottom and Fig. 10 at the top, form a general diagram of the electrical and pneumatic connections for one thousand line switches.

Referring first to Figs. 1 and 2, on the base 11 is a hollow standard 12, and on this is mounted a tubular cap 13 free to slide on the standard when compressed air is admitted or exhausted thru the pipe 14. These parts form a pneumatic motor which will hereafter be referred to as motor 13.

Secured rigidly on the lower part of 13 is a collar 15 of insulating material, and 45 slidably mounted thereon is a sleeve 16. Pins 17 secured in the collar 15 and extending thru slots 18 in the sleeve 16 limit the length of movement of the sleeve on the collar. A projection 19 on one side of the 50 sleeve 16 extends downward and rests on a piece of insulation when the line switch is in its normal or lower position.

Pivoted at 21 on the projection 19 is a bell crank 22, the horizontal parts of which rest

upon the pins 17. The vertical arm of the 55 bell crank is hinged at 23 so that the upper part 24 of this arm may move at right angles to the movement about the pivot 21. In Fig. 5 at the lower left hand portion, this bell crank is all that appears of the 60 second line switch, the other parts of this line switch being removed to show this view of the bell crank. On the upper end of the part 24 is a pin 25 and a hook 26 (Fig. 5), the purpose of which will appear later. 65

On the sleeve 16 opposite the projection 19 is another projection 27, and insulatingly supported on this projection are wipers 28 and 29 designed to engage the terminals of trunks leading to selector switches. 70

The motor 13, the wipers 28 and 29, and the parts illustrated below them in Fig. 1, constitute one line switch. One hundred such line switches arranged in a row constitute a group of line switches. Adjacent to such a group of line switches are pieces 30 of insulating material (Figs. 2 and 5), and mounted to slide in slots in these pieces are horizontal bars 31. Adjacent to pieces 30 are mounting plates 32 on which are supported sylphons 33, each connected to a different bar 31. A sylphon is a metallic device similar to an accordion which expands and contracts as air is admitted to or exhausted therefrom. 80

The bars 31 are thin flat strips which have one edge notched so as to leave projecting parts 34 as shown in Fig. 2. In one corner of each projection 34 is a hole 35 of a size and shape to receive the pin 25 on the part 24 of bell crank 22. When the sylphons 33 are in their contracted position, the bars 31 are supported so that the holes 35 in each are arranged vertically over each other and opposite the centers of the motors 13. When 90 a sylphon is expanded, the connected bar is shifted in the direction of the arrow so that its notches between projections 34 are opposite the centers of the motors 13. 95

Secured to each piece or plate 30 is a toothed bar 36 arranged to be engaged by the hook 26 whenever the part 24 of bell crank 22 moves on its hinge 23. 100

When compressed air is admitted to the motor 13, the collar 15 rises with the motor, but the sleeve 16 remains supported on the block 20 until the pins 17 reach the upper end of the slots 18. When this occurs, the 105

sleeve 16 and parts supported thereon rise with the motor. In the preliminary movement in which the pins 17 travel in slots 18, the bell crank is turned on its pivot so that 5 pin 25 is moved to a position directly under the adjacent vertical row of holes 35 in bars 31. If the lowest bar 31 is in its normal position, then pin 25 will enter hole 35, and the upward movement of the motor 10 13 will be arrested by contact between the bar 31 and the upper end of the part 24 of bell crank 22. If, however, the lowest bar has been shifted by its sylphon, then the adjacent projection 34 will not be in the 15 path of the bell crank, and the motor 13 will continue to rise until the bell crank finds some other bar 31 which has not been shifted. If, after engagement between a bell crank and a bar 31, the bar is shifted 20 by its sylphon 33, then the engagement between the pin 25 and hole 35 will move the part 24 on its hinge 23 so as to cause the hook 26 to engage toothed bar 36.

It is to be observed that if the lowest bar 25 31 is in its normal position, then any one of the adjacent line switches in rising will engage it and be stopped in that position. But if the lowest bar has been moved by its sylphon, then no line switch can engage it. 30 Any rising line switch would pass the lowest bar and be stopped by the second bar, or by the first bar it found in its normal position.

The trunk terminals are metallic strips arranged in pairs insulated from each other. 35 They are shown in transverse section in the upper right hand part of Fig. 1, and in side elevation in the upper part of Fig. 5. The wipers 28 and 29 are shown in engagement with normal contacts 40 which are alive for 40 certain conditions but which are dead as far as the present application goes. Above the contacts 40 are twenty pairs of terminals 41 which correspond to the twenty bars 31 and the twenty teeth on the racks 36. A group 45 of twenty bars and a group of twenty pairs of terminals extend adjacent to a group of one hundred line switches, and terminate where the group of line switches terminates. Similar groups of bars and terminals are 50 associated with each group of one hundred line switches. Some of the bars and terminals of one group are associated electrically and pneumatically with corresponding bars and terminals of other groups, but they 55 are separated mechanically.

Associated with and forming part of each line switch are a line relay having windings 42 and 51, a valve 53, a motor 74 and certain other parts which will be understood from 60 the description of the operation. The wires 46 and 47, at the lower right hand part of Fig. 1 extend to a local station where they are provided with means for being electrically connected to complete a circuit thru 65 the line relay. When this occurs a current

flows:—battery X—42—43—44—45—46—local station—47—48—49—50—51—ground.

This attracts armature 52 to open valve 53 and permit compressed air to flow from the general supply pipe 54 thru pipe 14 to the 70 motor 13 which immediately rises. In this movement upward the bell crank 22 is tilted forward as previously described and engages the first bar 31 found in its normal position. It will be assumed that this is this time the 75 lowest bar indicated by the numeral 64, whereupon a circuit is completed which may be traced on Fig. 6 as follows: battery Y— 55—56—57—58—59—60—61—magnet 62— 63—64—22—ground. 80

This attracts the armature 65 which is caught and held by the hook 66 which breaks the circuit for the magnet 62 at the springs 56—57. The movement of the armature 65 opens the valve 67 so as to permit air to 85 flow from pipe 54 thru pipe 68 to the sylphon 33 which is connected to the bar 64 of the group 31.

Adjacent to the magnet 62 is another magnet 71 which has a wire 72 extending to 90 the spring 73 Fig. 3 on the particular selector which is on the other end of the trunk found by the stoppage of the motor 13 when the bell crank 22 engages a bar 31. When the hook 66 Fig. 6 moves to catch armature 95 65, the shift in the adjacent contact springs connects the battery Y to spring 73 as follows: Y—55—56—69—70—71—72—73. (Figs. 2, 3 and 6).

When the sylphon operates by reason of 100 armature 65 opening valve 67 as described, it moves the associated bar longitudinally and causes the hook 26 on the part 24 to engage the teeth of the associated rack 36. When the opening of valve 53 admitted air 105 to motor 13 it also admitted air to motor 74 which is on a branch of pipe 14. But motor 74 is restrained by a stiff spring 75. Under these conditions, motor 74 will not operate as long as air flows freely to rising motor 110 13, but as soon as motor 13 is stopped by reason of its bell crank 22 engaging a bar 31, full pressure will flow to motor 74 and that motor will advance until hook 76 drops over the ring 77. When this occurs, the adjacent contact springs move to their alternative position and the station wires 46 and 47 are shifted from the line relay to the wipers 28 and 29. These wipers are at this 115 time on the terminals of the found trunk 120 represented by wires 78 and 79.

On each trunk at the selector is a relay corresponding to the line relay 42—51, and this relay is energized when the line wires 46 and 47 are connected to the wipers 28 and 29 in the same way that the relay 42—51 was previously energized. The relay thus energized on the selector opens a valve corresponding to valve 53, and this admits air to the motor 80 shown in Fig. 3. This motor 125 130

lifts arm 81 to raise cam 82 above the pin 83 on spring 73. These parts are held in this position until release occurs.

When the dropping of catch 76 Fig. 1 shifted the line wires to the wipers 28 and 29, it broke the circuit for the relay 42—51, and this in turn permitted the valve 53 to close and shut air from motors 13 and 74. But motor 13 is held by the previous engagement of hook 26 on ratchet 36, and motor 74 is held by catch 76 on ring 77. Consequently, the breaking of the circuit thru the line relay does nothing other than shut off the flow of electricity thru the relay and the flow of air to motors 13 and 74.

When the subscriber breaks the circuit at his station, the motor 80 on the selector falls back and in part of the descent of the arm 81 causes cam 82 to engage pin 83 and move spring 73 to engagement with grounded spring 84. When this occurs a current flows as follows: Y in Fig. 6—55—56—69—70—(Figs. 6 and 2)—71—72—(Figs. 6, 2 and 3)—73—84—ground.

This attracts armature 85 and causes it to release hook 66 from armature 65 which falls back and permits valve 67 to close; this shuts air from the sylphon 33 and permits spring 86 (Figs. 2 and 5) to return the moved bar 31 to its normal position. The return of this bar releases hook 26 from rack 36 and permits motor to fall to normal position. In thus falling, the projection 87 (Fig. 1) engages the tail of catch 76 to lift it from ring 77 and permit motor 74 to return to normal.

At the time the armature 85 moves the hook 66 from armature 65, it breaks the circuit for magnet 71 at springs 56—69, but at the same time remakes it at springs 87—88, when the circuit is: Y—55—87—88—70—71—72—73—(Fig. 3)—84—ground.

In arranging an exchange of one thousand subscribers I place the line switches in ten groups of one hundred each. When the line switches are measured by the trunks leading from them, the grouping is composite. For certain of the trunks, the line switches are in ten groups of one hundred each, for certain other trunks, the switches are in five groups of two hundred each; for still other trunks they are in two groups of five hundred each; and for a fourth class of trunks the switches are all in one group. Two or more trunks of each class are available for each line switch in the exchange, and Figs. 1 and 5 show a total of twenty trunks for each switch. This means that the present illustration is of twenty trunks divided into four classes of two or more in each class. In Figs. 6 to 10 I have shown two trunks for each class, the trunks being arranged for ten groups of line switches. It is to be understood that the actual trunks

of each class can be increased to any desired number, the two shown in each class being sufficient to make clear the manner of arranging them. It is also to be understood that the terminals 41 are arranged in the same way that the bars 31 are arranged, and that the wires leading from strips 41 and bars 31 are the three wires of a trunk. Also that, associated with each such three wires is an electrical and pneumatic unit such as shown in Fig. 2.

In the lower part of Fig. 6 there are shown eight bars 31 together with the sylphones by which they are moved. These eight represent two bars of each class. Below these bars are shown the electrical devices for one bar, it being understood that there are one hundred line switches in front of these bars. For convenience I designate the one hundred line switches in front of a distance covered by the length of a bar as a group of line switches, and the twenty bars (eight only shown) adjacent to the switches as a group of bars. But the division of these bars as will be explained, I call a division into classes.

In the upper part of Fig. 6 is a second group of bars 31 with which there is, of course, associated a group of one hundred line switches. Similarly, on each of the other diagram sheets are two groups of bars, and their connections.

Referring to the trunks of the first hundred in the lower half of Fig. 6, the lowest two bars 31 represent trunks which are limited to this hundred switches, and consequently the bars have no wires leading to other groups. Taking the next two bars 31 just above those mentioned, they have wires 90 and 91 leading to corresponding bars 31 in the second group on the upper half of Fig. 6. Consequently, while these bars of these two groups are mechanically separated they are electrically connected.

Taking the next two bars, it will be seen that they have wires 92 and 93 which may be traced thru Fig. 7 and the lower half of Fig. 8, in all of which places these wires have taps leading to corresponding located bars. This means that these bars in five different groups are electrically connected so that an electrical connection made to any one of them extends to all of the others.

The upper two bars have wires 94 and 95 which extend over the entire thousand and have taps connected to the upper two bars of each hundred. An electrical connection made to either bar in any of these groups extends to corresponding bars in all of the other groups.

In each of the other groups, the lowest two bars have no electrical connections extending to other groups, and consequently they are individual to their own groups. The second two bars of the third and fourth

hundreds are connected together by wires 96 and 97; the corresponding bars of the fifth and sixth hundreds are connected by wires 98 and 99; those of the seventh and 5 eighth by wires 100 and 101; and those of the ninth and tenth by wires 102 and 103. The last five hundred have corresponding bars connected together by wires 104 and 105.

Each bar 31 has its own sylphon 33, with 10 air connections to the general supply pipe 54. The lowest two bars of each hundred each has its own valve 67 operated by its own magnet 62 for letting air flow to its own sylphon. These are the bars which 15 have no wires extending to corresponding bars in other groups. Consequently, each of these bars is independent, both electrically and pneumatically, of what happens to other bars.

20 The sylphons of the second two bars of the first and second hundreds are connected together by pipes 106 and 107; the corresponding sylphons of the third and fourth hundreds are connected by pipes 108 and 109; 25 and other corresponding sylphons are connected by pipes 110 and 111, pipes 112 and 113, and pipes 114 and 115. By comparisons it will be seen that the bars of different groups are interconnected pneumatically in the same way that they are connected electrically thru the wires previously described. Hence, it will not be necessary 30 to describe all of the pipe connections in detail. They can be traced on the drawings.

35 The pipe 107 receives air from the main pipe 54 thru a valve 67^a which is operated by a magnet 62 associated with the trunk involved. A part of the armature of this magnet is shown at 65^a. By inspection it 40 will be seen that this pipe 107 connects to the third sylphon in both groups shown in Fig. 6, and that when the valve 67^a is opened, the corresponding bars of both groups are shifted by their sylphons so that no moving 45 line switch in either group will be stopped by a bar in the third position. These bars are the ones interconnected by the wire 91.

In the previous description it was assumed that the line switch of Fig. 1 was 50 stopped by the first or lowest bar which was given the special reference character 64 to distinguish it from others for convenience. Because this bar (and the next one above it) has no connection to any other 55 group, it alone is shifted when air is admitted to the sylphon shown in Fig. 2. But if we assume that the lower two bars had been shifted and that the rising line switch had engaged the third bar, then the valve 60 opened by the corresponding magnet 71 would admit air to the third sylphon of two groups. From this it will be apparent that one magnet 62 with corresponding valve is sufficient for the simultaneous movement of 65 two or more bars when they have their

sylphons connected to a pipe controlled by the valve. The connection 91 between the bars makes it evident that a wire such as 70 63 extending to the magnet 62 may come from either bar or from the interconnecting wire 91.

The first or lowest bar of each of the ten groups is part of an independent trunk extending to a different selector. The same is 75 true of the second bar. But the third bars in the first and second groups taken together constitute part of one trunk leading to one selector; the third bars of the third and fourth groups constitute part of another trunk; and so on. And the same thing is 80 true of the fourth bars of the various groups as may be seen by the interconnecting wires and pipes.

In the same way the fifth bars of the first 85 five groups constitute part of one trunk, and the sixth bars of the same groups constitute part of another trunk. The same is true of the fifth and sixth bars of the last five groups. The seventh bars of all of the 90 groups are parts of the terminals of one trunk, and the eighth bars are parts of the terminals of another trunk.

A point to be noted is that the release of a line switch is by the return movement of the bar 31 to which it has made connection, and 95 that these bars are controlled by the valves 67, 67^a, etc., which admit air to the sylphons 33. These valves in turn are controlled by the magnets 62, there being one such magnet 100 for each valve. By inspection of the air connections on Figs. 6 to 10 it will be seen that the magnets and valves involved in releasing the line switches are not as numerous as the switches to be released, and not even as numerous as the bars to which the line switches 105 make connection. The release mechanisms, meaning magnets 71 and parts controlled thereby, are as numerous only as the trunks to which the switches connect, and some trunks terminate at several bars 31. Any 110 line switch may connect to the top bar of its group, and as all top bars are interconnected by wire and pipe and controlled by a single magnet and valve, it is evident that every 115 switch in the thousand is capable of being released by the same release mechanism.

What I claim is:

1. In a telephone exchange, a series of line switches, a movable element for each of said line switches, a series of bars each of which has projections in the path of each of said elements when said elements are moved from their normal positions, means for moving said elements from their normal positions, a 120 pneumatic device associated with each bar for moving it so as to remove its projections from the paths of said elements, magnets associated with said bars for controlling the admission of air to said pneumatic devices, and means for closing the circuit for one of 125 130

said magnets by contact between one of said elements and the bar with which said magnet is associated.

2. A line switch having an element arranged to be moved from normal position by air pressure, a motor for moving said element, means for stopping said element in connection with an idle trunk, a pneumatic device for shifting the stopping means laterally when the idle trunk is reached, and a catch operated by such lateral movement and serving to support said element in its operated position after the air pressure is withdrawn.

15 3. In a switching mechanism, wipers, a power device for moving them, a series of stopping devices any one of which when in normal position will stop the movement of the wipers and remove the source of power therefrom, and a holding device operated by a stopping device and arranged to retain the wipers in arrested position after the power is removed.

4. A motor, a series of stopping devices, an arm carried by the motor, and a sliding connection between the motor and the arm operated by the motor to move said arm toward or from the stopping devices.

5. A series of groups of line switches and means for moving them, a series of stopping devices for each group of switches any device of which will serve to stop the movement of any switch of its group, and means by which one engagement between a line switch and a stopping device will automatically cause the removal of corresponding stopping devices in two groups.

6. A group of line switches, a group of bars each of which has a projection in the path of each line switch when said line switches are moved from their normal positions, a series of such groups, means for moving any bar so as to remove its projections from the paths of the line switches, and means by which an engagement between a line switch and a bar will automatically cause the movement of that bar and a corresponding bar in another group so as to remove the projections of both from the paths of line switches.

7. A group of bars, a pneumatic device associated with each bar for moving it from normal position, a series of such groups, and means by which an electrical connection made to one bar will cause the bar to be moved and also cause the movement of another bar in another group.

8. In a line switch controlling apparatus, a series of groups of bars, a pneumatic device connected to each bar for moving it, interconnections between certain bars of one group and corresponding bars of other groups, and means by which upon a line switch engaging an interconnected bar the pneumatic devices of that bar and the one

or more bars with which it is interconnected will operate to move their bars.

9. In a line switch controlling apparatus, bars located at different places adjacent to the line switches to be controlled, a pneumatic device connected to each bar for moving it, an air pipe connecting two such pneumatic devices, a valve for admitting compressed air to said pipe, and means for controlling said valve by contact of any line switch with either of the bars having connected pneumatic devices.

10. In a line switch controlling apparatus, bars located at different places adjacent to the line switches to be controlled, a pneumatic device connected to each bar for moving it, air pipes connecting certain pneumatic devices in pairs, an air valve connected to each pipe, electrical connections between bars corresponding to the pipe connections between pneumatic devices, and means for controlling each air valve by an electrical impulse flowing over the corresponding electrical connection.

11. In a line switch controlling apparatus, bars adjacent to the switches and serving to stop them, a motor connected to each bar and serving to move it from position in which it will stop a line switch, interconnections between certain motors so arranged as to cause a plurality of motors to operate simultaneously, and interconnections between bars to correspond with the interconnections between motors.

12. In a line switch controlling apparatus, bars for controlling the line switches, a motor connected to each bar for moving it, interconnections between certain motors so arranged as to cause two or more of them to operate simultaneously, similar interconnections between bars, and means for controlling the motors thru the interconnections to the bars.

13. A series of line switches, devices common to and controlling the series of line switches, a motor connected to each device for moving it, and interconnections for causing a plurality of motors to operate simultaneously.

14. A series of line switches, trunk terminals therefor, means for moving the line switches, devices for stopping the line switches on a trunk terminal, and means for operating a plurality of said devices simultaneously.

15. A series of line switches, trunk terminals therefor, devices which in their normal positions control the operation of said line switches to select an idle trunk terminal, means for operating a plurality of said devices simultaneously, and means for controlling such operation by a moving line switch.

16. A series of line switches, a series of devices each one of which in its normal posi-

- tion serves as a means for stopping any one of a plurality of line switches, means for simultaneously removing a plurality of said devices from their normal position, and 5 means for controlling the removing means by the stoppage of a line switch.
17. A series of groups of line switches, trunk lines accessible thereto, a device for stopping any line switch within a group on 10 an idle trunk line, another device for stopping any line switch within a plurality of groups on an idle trunk line, and means by which upon a line switch engaging either of said devices the engaged device will be automatically moved from normal position.
18. A series of line switches divided into groups, a series of trunks having terminals at the line switches, said trunks being divided into classes part of which classes have terminals at a plurality of groups of line switches, and switch stopping devices divided into classes which correspond to the classes into which the trunks are divided, said devices in their normal positions adapted to stop the trunk hunting operation of 20 said line switches.
19. A series of line switches divided into groups, and a series of switch controlling devices divided into classes, one class of 30 which corresponds to the groups and another class of which corresponds to a plurality of groups, said devices in their normal positions adapted to stop the trunk hunting operation of said line switches.
20. A series of line switches divided into groups, a series of switch stopping devices divided into corresponding groups, part of the switching stopping devices of one group being permanently connected to corresponding 40 switch stopping devices of another group so that the stopping devices become divided into classes which do not correspond to the groups, and means for controlling the stopping devices by the classes into which they are divided.
21. In a telephone exchange, the combination with a series of pneumatically operated line switches, a less numerous series of trunks, selector switches and means for operating the line switches to automatically 50 select idle trunks, of a release mechanism separate from said selector switches and associated with each trunk, and means by which the mechanism of a trunk serves as a means for releasing any line switch which may have selected that trunk.
22. In a telephone exchange, a series of pneumatically operated line switches, a less 60 numerous series of trunks to which said line switches may be connected, selector switches and a releasing mechanism for each trunk separate from said selector switches, each releasing mechanism being arranged to release any line switch which may become connected to the corresponding trunk.
23. The combination with a plurality of pneumatically operated line switches and means for advancing them from normal position, of selector switches and a series of releasing devices each one of which is arranged so that it may release any one of a plurality of said line switches, said releasing devices separate from said selector switches. 70
24. A series of pneumatic line switches and a series of releasing mechanisms, selector switches separate from said releasing mechanisms, said line switches and mechanisms being so constructed that the same line switch may be released by any one of a plurality of mechanisms and the same mechanism may release any one of a plurality of line switches. 75
25. In a telephone system, line switches divided into groups, wipers and bank contacts for each switch, trunk lines, one group of said trunk lines connected to the banks of only one group of switches and another group connected to the banks of a plurality of groups of switches, a stopping device 80 common to the trunks of said first group and a stopping device common to the trunks of the other group for stopping the switches in engagement with one of said trunk lines. 85
26. In a telephone system, two motors with a common connection, a device for admitting a source of energy to said connection to cause the operation of said motors, one of said motors arranged to operate under a less amount of energy than the other motor whereby said other motor does not receive enough energy to cause it to operate until said first motor has had its movement arrested. 90
27. In a telephone system, the combination of a motor having a variable movement, a second motor having a fixed movement and a device for admitting a source of energy to both of said motors, of means for retaining the second motor in unmoved position 95 until after the first motor has completed its movement. 100
28. In a telephone system, the combination with two motors having a common connection, of a device for admitting a source of energy to said common connection to operate said motors, and means for holding one of said motors inoperative until the other of said motors has been moved and stopped. 115
29. In a telephone system, an automatic switch having two motors, a device for admitting a source of energy to said motors at the same time for causing the operation of said motors, and means for holding one of said motors inoperative until the other of said motors has been moved and stopped. 120
30. In a telephone system, a series of line switches, devices for controlling the series of line switches, a pneumatic motor connected to each device for moving it, and inter- 125

connections for causing a plurality of motors to operate simultaneously.

31. In a telephone system, a series of line switches, trunk terminals therefor, devices, common to said line switches, said devices for stopping said line switches on a trunk terminal, and means for operating a plurality of said devices simultaneously.

32. In a telephone exchange, a series of line switches, a movable element on each of said line switches, a series of bars each of which has a projection in the path of each

of said movable elements when said elements are moved from their normal positions, means for moving said elements from their normal positions, a pneumatic device associated with each bar for moving it so as to remove its projections from the paths of said elements, magnets associated with said bars for controlling the admission of air to said pneumatic devices, and means for energizing any one of said magnets.
